DISCHARGE CHUTE ASSEMBLY FOR CONCRETE MIXERS OR THE LIKE

Louis J. Sarosdy, Pittsburgh, Pa., assignor to Blaw-Knox Company, Pittsburgh, Pa., a corporation of New Jersey

Application January 31, 1949, Serial No. 73,685

6 Claims. (Cl. 193—10)

1

This invention relates to a new discharge chute assembly for concrete mixers or the like. More particularly, it relates to a removable discharge chute assembly for use with high discharge type transit vehicle mixers in which a gathering pan maintains its proximate positioning to the discharge spout of the mixer irrespective of the horizontal and vertical angularity of a discharge chute pivoted thereto, and in which the support for such assembly can be swung out of the way when not in use.

High discharge type transit mixers usually comprise a mixing drum the axis of which inclines upwardly toward the rear of the vehicle. This drum is supported in a sturdy frame and has the discharge opening of the drum at the upper end of the axis. A discharge spout is provided around this opening to guide the material, such as concrete or the like, into suitable discharge chutes. In some cases such discharge spouts are of the type which can be rotated independently of the drum so that the spout serves both as a charging hopper and as a discharging spout dependent upon the angular position thereof around the axis of the drum. Discharge from such a revolvable discharge spout sometimes may occur before it is in directly downward position. This means that the material being discharged from the drum begins to fall at some distance away from the vertical plane through the longitudinal center line of the vehicle. Moreover, for placement of the material from the mixer it is desirable to guide the stream of material issuing from the drum to any selected point within an arc of approximately 180° around the rear of the vehicle.

Heretofore, removable discharge chutes have been used which are rotatable to effect such distribution. Sometimes these chutes are of a single length or of more than one connected length. Furthermore, provision has been made to have the upper end of such chutes positioned beneath the discharge spouts of the mixer. However, with each change in slope of said chute the distance between the spout and the upper end of the chute varies correspondingly. Moreover, with revolvable hopper spouts, it is not practical to make the upper end of such discharge chutes sufficiently wide to catch material from the spout in all of the positions it may have when some discharge occurs. Still further, where the supporting of such chutes has involved the use of an extension frame attached to the mixer vehicle, there is no provision for the discharge of material by the free fall thereof from the spout

2

into a receiving conduit or form not connected to the vehicle without interference from said extension frame.

In the present invention, these difficulties are overcome. Irrespective of the horizontal and vertical angularity of the discharge chute in an assembly made in accordance with this invention, the receiving end of the discharge assembly remains beneath and in the same proximate vertical relationship to the discharge spout of the mixer. This is true whether the discharge spout is revolvable or not. Moreover, the structure of this invention is so made that material can be discharged by free fall directly into conduits, forms or receptacles not attached to the mixer or its frame. Other objects and advantages of this invention will appear from the following description and from the following drawings, which are illustrative only, in which

20 Figure 1 is a view in elevation of a discharge assembly made in accordance with this invention and mounted on the back of a high discharge type of transit concrete mixer;

25 Figure 2 is an enlarged view of the apparatus shown in Figure 1 which illustrates by dotted lines the traveling position of the support for the arcuate gathering pan and the discharge chute when the latter are removed;

Figure 3 is a view in elevation taken along lines 30 III—III of Figure 2;

Figure 4 is a view taken along lines IV—IV of Figure 2;

Figure 5 is a view in cross section taken along line V—V of Figure 2; and

35 Figure 6 is a view in cross section taken along line VI—VI of Figure 5.

Referring to Figures 1 and 2, a drum 10 of a high discharge type of transit mixer vehicle for concrete or the like has an integral supporting ring 11 which rides on roller bearings (not shown) journaled in upper frame members 12. Upper frame members 12 are an offset continuation of lower vertical frame members 13 integrally riveted or welded to a crosspiece 14 and longitudinal frame members 15 all of which members 12, 13, 14 and 15 constitute a portion of the frame of the said vehicle.

The upper end of drum 10 terminates in a ring 16 which coengages a sealing ring 17 which 50 slides around ring 16 in interlocked and sealed relation thereto. Sealing ring 17 is affixed by brackets 18 to a discharge spout 19. Discharge spout 19 is a revolvable hopper shown in discharge position in solid lines in Figure 1 and in charging 55 position in chain-lines. The foregoing particular

structural features are not specific elements of the new discharge assembly of this invention.

A cylindrical cross member 20 horizontally spans the distance between the two vertical frame members 13. These frame members 13 also have welded thereto two extension brackets 21, suitably shaped for strength and rigidity. Plates 22 comprising the opposed vertical surfaces of brackets 21 are drilled respectively and in registry at 23 adjacent the lower edge thereof and at 24 adjacent the upper edge thereof. A pyramidal support 25 has two integral vertical supporting arms 26 and connecting bottom and top plates 27 and 28 respectively which complete the support 25. The inner ends of arms 26 fit between plates 22 and are drilled on centers corresponding to the centers of openings 23 and 24 respectively. A sleeve 29 connects the lower pair of openings in support 25 to which it is welded. A similar sleeve 30 connects the upper pair of openings in support 25. A pin 31 is assembled through sleeve 29 and journaled in openings 23 where it is held in lateral position by cotter pins 32. Washers 33 space support 25 in the center of the distance between plates 22. Another similar pin 34 is assembled through sleeve 30 and is journaled in openings 24. Cotter pins 35 maintain pin 34 in place. The fit of pin 34 is sufficiently easy so that it can readily be withdrawn upon the removal of one of the cotter pins 35. At the outer end of support 25 a socket 36 is welded. The axis of socket 36 is vertical when support 25 is in the position shown in Figure 1 with pins 31 and 34 in place.

When pin 34 is withdrawn, support 25 can be swung upwardly and toward drum 10 until socket 36 rests against cross member 20 as illustrated by chain lines in Figure 2. In this latter position, support 25 and socket 36 are wholly removed from beneath discharge spout 19 so that any material discharged therefrom under such circumstances will fall freely into a receiving conduit, form, hopper or other receptacle not connected with the vehicle on which drum 10 is mounted.

A hollow shaft 37 has a bearing flange 38 adapted to be rotatably supported in the vertical socket or sleeve 36 when support 25 is in the position shown in Figure 1. In such support, the underside of flange 38 bears against the upper annular edge of socket 36. Welded to the upper side of flange 38 are two supporting webs 39 which support an arcuate funnel 40. Webs 39 are welded or otherwise affixed to funnel 40. Funnel 40 serves as a gathering pan for discharge spout 19 and is somewhat offset toward drum 10 of the mixer from the vertical axis of hollow shaft 37. The outer upper perimeter or edge 41 of funnel 40 is substantially circular and in a horizontal plane. The lower discharge edge 42 is connected to the upper edge 41 by the curved substantially single surface 43 which terminates in a vertical portion 44 at the rear of the funnel. The forward face of funnel 40 is open so that this funnel which is substantially arcuate or fan shaped when viewed in plan is somewhat like a half of a semispherical bowl.

Funnel 40 is drilled at 45 adjacent lower edge 42 which openings are connected by a hinge sleeve 46 welded to the respective webs around each such opening. A discharge chute 47 has an upper end 48 and a lower end 49. Upper end 48 is sufficiently wide to receive all material gathered and discharged over lower edge 42. In turn, the radius of upper edge 41 is sufficiently large to catch all discharge from spout 19 even if such

discharge should commence before the spout reaches the full discharge position shown in Figure 1. This is so irrespective of the angular horizontal position of gathering pan 40.

5 A plate 49' is welded to the underside of upper end 48. Two ears 50 integral with plate 49' span the distance between the outer sides of webs 39 and are drilled in registry with openings 45. A hinge-pin 51 having a head 52 and a retaining chain 53 can be inserted respectively through ears 50, openings 45 and sleeve 46 to hold discharge chute 47 in fixed position relative any horizontal rotation of pan 40. A cotter pin inserted through hole 54 prevents the removal of hinge-pin 51 until desired.

The slope of discharge chute 47 can, however, be varied for each horizontal angular position of funnel 40. Recesses or notches 55 above pivot bearing openings 45 provide clearance for the 20 upper edge of chute 47 for the various slopes which chute 47 may be caused to assume. This upper edge of upper end 48 is beneath and in overlapping relation to lower edge 42 of gathering pan 40.

25 A plate 56 is welded to the underside of chute 47 intermediate the ends thereof as illustrated in Figures 1 and 2. This plate has a bracket 57 extending toward drum 10 of the mixer for pivotal connection at 58 with a brace 59. Pivotal connection 58 which is journaled in bracket 57 and held in position by cotter pins (not shown) or other suitable means, can be disassembled if it is desirable to separate brace 59 from chute 47 for transportation or repair purposes. Adjacent the inner end of brace 59 a series of holes 60 are drilled at spaced intervals. These holes cooperate in fixing the position of brace 59 relative to shaft 37 to determine the slope of chute 47.

35 The lower end of hollow shaft 37 is slotted at 40 61 upwardly from the bottom along diametrically opposed longitudinal portions of the shaft walls. The width of the slots 61 is sufficient to accommodate the diameter of brace 59 as shown in Figure 6. Two guide bars 62 are riveted to shaft 37 and extend across it in a vertical plane normal to the plane connecting slots 61. Lower guide bar 62 may also be made removable if required to facilitate the disengagement of brace 59 and slots 61.

45 A pin 63 having an enlarged head 64 is fastened to the lower end of shaft 37 by a retaining chain 65. The inner end of brace 59 is slid through slot 61 between guide bars 62 until the desired slope of chute 47 is obtained. To hold discharge chute 47 in that position pin 63 is inserted through the 50 adjacent hole 60 on the outer side of shaft 37 as shown in Figures 1 and 2 and thus serves as a stop to maintain chute 47 in its predetermined desired sloping position. A cotter pin can be inserted through a hole 66 at the lower end of pin 63 to lock chute 47 in position.

55 Intermediate the ends of shaft 37 a series of radial holes 67 are drilled completely through the shaft, as shown in Figure 5. These holes have their centers on the same horizontal plane when the shaft is in operative position. A further pair of radial holes 68 is drilled completely through sleeve 36 in the same plane when in operative position as the plane in which holes 67 lie. Holes 68 are also offset from the vertical center line plane of support 25. In this way, a key 69 can be used to lock shaft 37 in any of the number of horizontal angular positions afforded by the number of pairs of diametrically opposite holes 67 in shaft 37. In operation, key 69 is inserted through holes 68 and a registering pair of holes 67 as illus-

trated in Figures 5 and 6. The head of key 69 is drilled for the reception of a loose fitting rivet 70. The other end of key 69 is pointed for ease of insertion. Rivet 70 is sufficiently enlarged at both ends so that it cannot become disengaged from key 69. A retaining chain 71 is welded to the head of rivet 70 and to socket 36 to prevent loss of the key when it is removed for disassembly of the discharge mechanism or for rotation of the discharge mechanism to a different horizontal angular position around the approximate semicircle to the rear of the mixer in which distribution can be made as a practical matter by chute 41. An outstanding lug 72 is welded to sleeve 36 and has an opening 73 immediately below the axis of rivet 70 when key 69 is in inserted position. Opening 73 is in such proximate relation to rivet 70 that the lower end thereof passes through the said opening and holds key 69 against any dislodgment during operation which might otherwise be caused by vibration or the jarring of the associated machinery and mechanism.

Thus, arcuate gathering pan 40 retains its proximate position beneath discharge spout 19 for every horizontal angular position of shaft 37. Moreover, for each such horizontal angular position discharge chute 47 can be caused to assume a variety of slopes dependent on the particular point of distribution to be reached by lower end 49 of chute 47. This lower end terminates in a coupling collar 74 having laterally outwardly extending trunnion pins 75 to which a chute extension can be attached in a conventional manner. The slope of chute 47 is, of course, determined by the stop position effected by pin 63 against shaft 37. When it is desired to have material discharged from spout 19 fall directly down into a receiving conduit or other receiving member not connected to the vehicle on which drum 10 is mounted and without loss of material by splattering or flowing over any portion attached to that vehicle, pin 51 is withdrawn and then chute 47 and brace 59 are removed. Then pan 40 is turned after the withdrawal of key 69 so that shaft 37 can be lifted out of sleeve 36. Pin 34 is then removed and support 25 and socket 36 are swung toward frame members 13 until they come to rest in the position shown in Figure 2. These various members are light enough to be manipulated in this way.

Although I have illustrated and described but a preferred embodiment of the invention, it will be recognized that changes in the details of construction disclosed may be made without departing from the spirit of the invention or the scope of the appended claims.

I claim:

1. In a discharge assembly for concrete mixers or the like having a discharge spout, in combination, a gathering pan adapted to be positioned beneath said spout, said pan having an upper arcuate edge and a lower discharge edge, said edges being connected by a surface generally sloping toward said discharge edge, a generally vertical shaft connected substantially solely to the outside of said pan, a socket for rotatably supporting said shaft, said socket being connected to said concrete mixer or the like, said shaft and socket enabling said pan to be horizontally rotated while remaining beneath said spout, and a chute pivotally connected to said pan adjacent said discharge edge.

2. In a discharge assembly for concrete mixers or the like having a discharge spout, in combination, a gathering pan adapted to be positioned beneath said spout, said pan having an upper

arcuate outer edge and a lower discharge inner edge, said edges being connected by a surface generally sloping toward said discharge edge, a generally vertical shaft connected substantially solely to the outside of said pan, a socket for rotatably supporting said shaft, said socket being connected to said concrete mixer or the like, and a chute pivotally connected to said pan about a horizontal axis and extending beneath at least the lower portion of said discharge edge.

3. In a discharge assembly for concrete mixers or the like having a discharge spout, in combination, a gathering pan adapted to be positioned beneath said spout, said pan having an upper arcuate outer edge and a lower discharge inner edge, said edges being connected by a generally continuous curved surface sloping toward said discharge edge, at least one generally vertical web rigidly connected substantially solely to the underside of said pan, a generally vertical shaft rigidly connected to said web below said pan, a socket for rotatably supporting said shaft, said socket being pivotally connected to said concrete mixer or the like, and a chute pivotally connected to said web about a horizontal axis and extending beneath at least the lower portion of said discharge edge.

4. In a discharge assembly for concrete mixers or the like having a discharge spout, in combination, a gathering pan adapted to be positioned beneath said spout, said pan having an upper arcuate edge and a lower discharge edge, said edges being connected by a surface generally sloping toward said discharge edge, a generally vertical shaft connected substantially solely to the outside of said pan, a socket for rotatably supporting said shaft, said socket being connected to said concrete mixer or the like, said shaft being recessed in the lower portion thereof extending below said socket, a chute pivotally connected to said pan and extending beneath at least the lower portion of said discharge edge, a brace pivotally connected to the underside of said chute, the other end of said brace extending through said recess, and means for varying the length of said brace between said shaft and said chute.

5. In a discharge assembly for concrete mixers or the like having a discharge spout, in combination, a gathering pan adapted to be positioned beneath said spout, said pan having an upper arcuate edge and a lower discharge edge, said edges being connected by a surface generally sloping toward said discharge edge, a generally vertical shaft connected solely to the underside of said pan, a socket for rotatably supporting said shaft, a polyhedral support rigidly connected to said socket, said support being pivotally connected to said concrete mixer or the like about a horizontal axis to enable it to be vertically swung from beneath said spout when said pan is not being used.

6. In a discharge assembly for concrete mixers or the like having a discharge spout, in combination, a gathering pan adapted to be positioned beneath said spout, said pan having an upper arcuate outer edge and a lower discharge inner edge, said edges being connected by a surface generally sloping toward said discharge edge, a generally vertical shaft connected substantially solely to the underside of said pan, a socket for rotatably supporting said shaft, keying means for engaging said socket and shaft to fix said pan in the horizontal position to which it may be swung, a polyhedral support rigidly connected to said socket, and spaced generally vertical

brackets rigidly connected to said concrete mixer or the like and extending generally in the direction of said spout, said support being pivotally connected to said brackets about a horizontal axis to enable it to be vertically swung from beneath said spout when said pan is not being used.
